CLAIM

The ornamental design for an automobile, as shown and described.

DESCRIPTION

FIG. 1 is a top, front and left side perspective view of an automobile showing my new my design;

FIG. 2 is a front elevation view thereof;

FIG. 3 is a rear elevation view thereof;

FIG. 4 is a top plan view thereof;

FIG. 5 is a left side elevation view thereof;

FIG. 6 is a right side elevation view thereof; and,

FIG. 7 is a top, rear and right side perspective view thereof.

The broken lines shown in the drawings illustrate portions of the automobile that form no part of the claimed design.
